UNITED STATES PATENT OFFICE.

JESSE H. PERRAULT, OF DETROIT, MICHIGAN.

PAPER BOTTLE AND PROCESS OF MANUFACTURING SAME.

1,265,505.

Specification of Letters Patent.

Patented May 7, 1918.

Application filed January 19, 1916. Serial No. 73,002.

To all whom it may concern:

Be it known that I, JESSE H. PERRAULT, a citizen of the United States, residing at Detroit, Wayne county, Michigan, have invented 5 certain new and useful Improvements in Paper Bottles and Processes of Manufacturing Same, of which the following is a specification.

This invention relates to improvements 10 in paper bottles and the process of manufacturing the same, particularly to multiple ply paper bottles which are especially adapted for use as milk bottles, although of course they may be used for a variety of purposes.

15 The objects of the invention are,

First, to provide an improved construction of multiple ply paper bottle which can be very readily manufactured.

Second, to provide an improved breast 20 and neck construction for such bottle.

Third, to provide an improved bottom construction for such bottle.

25 Further objects and objects relating to details and economies of construction and operation will definitely appear from the detailed description to follow.

I accomplish the objects of my invention by the devices and means described in the following specification. The invention is 30 clearly defined and pointed out in the claims.

Structures illustrating preferred embodiments of my invention are shown in the accompanying drawings, forming a part of this specification, in which:

35 Figure I is an elevation view of a bottle embodying the features of my invention.

Fig. II is an enlarged detail transverse sectional view taken on a line corresponding to line 2—2 of Fig. I.

40 Fig. III is an enlarged detail sectional view taken on a line corresponding to line 3—3 of Figs. I and V, showing the details of the arrangement of the folds in the paper.

Fig. IV is an enlarged detail sectional view taken on a line corresponding to line 4—4 of Fig. I, showing details of construction of the bottom portion.

Fig. V is an enlarged detail sectional view taken on a line corresponding to line 5—5 50 of Figs. I and III.

Fig. VI is an enlarged detail sectional view, taken on a line corresponding to line 3—3 of Figs. I and V, of a modified form of the wall structure of the neck.

55 Fig. VII is a detail sectional view similar

to that of Fig. IV, showing a modification of the bottom in that it is not embraced in the bottom crease.

Figs. VIII, IX, X, XI and XII are details of modifications of the formation of the neck part, particularly in regard to reinforcing the same and to the formation of the groove in the cap.

In the drawings, similar numerals of reference refer to similar parts throughout the several views, and the sectional views are taken looking in the direction of the little arrows at the ends of the section lines.

Considering the numbered parts of the drawing the body of the bottle 1 is cylindrical in form, made up of plies 2 of paper which are creased and conformed into the breast of the bottle at 3 and rolled into a cylindrical neck 4 in which is formed an angular crease 5, the same being formed lengthwise of the fibers of the paper. The neck is expanded at 6 and the cap 7 is inserted in the crease, as seen in Fig. V.

Each layer of paper is creased in forming the neck, as seen at 4', and the creased portions overlapping each other break joints and make a very secure breast and neck to the bottle, the whole being rolled from a sheet and conformed by hot rollers with suitable cement to shape the same, and the whole being thereafter suitably paraffined.

The groove 5 has an angular portion at 8 with a downwardly sloping portion to receive the cap, like the structure described in my concurrent patent application filed January 19, 1916, Serial No. 73,003.

The bottom of the walls of the cylindrical portion of the bottle is folded back on itself with portions at 10 within which is inserted the bottom 11 with a downwardly projecting flange 12, the whole being crimped by suitable die rolls at 9 to retain the parts securely in place and to increase the rigidity of the bottom. The whole structure is then paraffined.

In Fig. VII I show a modification of this bottom, similar to Fig. IV, in which the bottom is not flanged and extended between the bottom folds, the flange 12 being merely omitted.

In Fig. VI I show a modification of the wall structure of the neck, similar to Fig. III, in which the double plies are creased together. This makes a much less secure structure than that of the preferred form,

requiring an extra operation. I wish to claim specifically the preferred form and also a claim sufficiently broad to embrace both structures.

5 In Fig. VIII a modification is shown in which the bottle is formed of a single ply. In Fig. IX the bottle is shown formed of double plies, the upper portion being folded back as a reinforce and finish, the edge forming a portion of the retaining groove, it not being necessary in this form to make the sharp angle in the wall of the paper.

10 In Fig. X I show a structure like that appearing in Fig. IX with the angle in the groove. In Fig. XI I show the finish at the 15 top of the bottle formed by folding the ply of the wall outward, the wall being of single ply. In Fig. XII I show a single ply wall with the top folded inward and extended 20 down as a reinforce and finish, the edge assisting in forming the groove for the cap.

I have thus described the structure in its preferred form. It will be seen that it is possible to wrap this paper directly onto a 25 mandrel or form, crease the same as it is paid out, forming the bottle of one or more plies, and then paraffin the same. The bottom should be preferably retained as I have indicated in Fig. IV, but may be otherwise 30 inserted. The variations that I have described show that the structure can be considerably modified without departing from my invention. I desire, however, to claim the same specifically as well as broadly as 35 pointed out in the appended claims.

Having thus described my invention what I claim is new and desire to secure by Letters Patent is:

1. The process of forming a bottle consisting in forming a cylindrical body of a plurality of plies of paper, separately creasing the plies at one end of said body to form plaits and rolling said plaits in overlapping relation to form the breast and neck of said 45 bottle, and pressing a groove in the neck of

said bottle to hold the plies together and to receive a cap.

2. The process of forming a bottle of paper consisting in rolling the paper to form the cylindrical body, inserting the bottom 50 with a downwardly projecting flange, folding the bottom walls of the bottle onto the same, and creasing the same, as specified.

3. A paper bottle made up of a plurality of plies, the breast of the bottle formed by 55 creasing the separate plies and overlapping the same, and a retaining groove for the cap formed in the neck of the bottle, as specified.

4. A bottle formed of one or more plies of 60 paper and a bottom for said bottle with a flange extended downwardly and the sides of said bottle being folded and creased onto the said flange.

5. A bottle made up of one or more plies 65 of paper, with a neck formed by plaiting the paper and overlapping the same in layers, with a groove for the cap formed therein.

6. A bottle comprising body, neck, and breast portions formed with a plurality of 70 plies of paper, the neck and breast portions having a plurality of plaits in each of the plies thereof rolled in overlapping relation.

7. A bottle made up of plies of paper 75 plaited and overlapping with the fibers of the paper disposed transversely to the bottle, suitably cemented together, as specified.

8. A bottle made up of one or more plies 80 of paper, the fibers of which are disposed transversely to the bottle, with a neck formed by plaiting the paper and overlapping the same in layers, with a groove for the cap formed therein.

In witness whereof, I have hereunto set my hand and seal in the presence of two 85 witnesses.

JESSE H. PERRAULT. [L.S.]
